UNITED STATES PATENT OFFICE.

NAZARENO SCICCHITANI, OF NEW ROCHELLE, NEW YORK.

SAFETY WINDOW-CHAIR.

1,098,127.

Specification of Letters Patent. Patented May 26, 1914.

Application filed May 24, 1913. Serial No. 769,616.

To all whom it may concern:

Be it known that I, NAZARENO SCICCHITANI, a citizen of the United States, and resident of New Rochelle, in the county of 5 Westchester and State of New York, have invented certain new and useful Improvements in Safety Window-Chairs, of which the following is a specification.

The object of my invention is to provide 10 simple and efficient means to enable a chair or seat to be secured within a window frame, as over the window sill, to enable a person to sit in the window upon the chair with safety.

15 In carrying out my invention I provide a window frame or sill with a retainer, over which I place a chair or seat having one or more members to coact with said retainer, and to the chair or seat I attach a clamping device adapted, when set to press against the window sill, to retain said members connected to said retainer, whereby the chair will be firmly clamped in position upon the window frame or sill. The chair is prefer- 20 ably provided with a suitable back and one or more legs to rest upon the outer sill or stone-work of the building, whereby a person may sit in the window upon the chair or seat, and may raise or lower the window 25 sashes as required for cleaning the latter, etc.

30 My invention comprises novel details of improvement and combinations of parts that will be more fully hereinafter set forth and then pointed out in the claims.

35 Reference is to be had to the accompanying drawings forming part hereof, wherein—

Figure 1 is an inverted plan view of a chair or seat equipped with my improvements; Fig. 2 is a cross sectional view illustrating 40 my improvements in position in a window; Fig. 3 is a front view thereof; Fig. 4 is a section on the line 4, 4, in Fig. 2; Fig. 5 is a detail illustrating a modification; Fig. 6 is a plan view illustrating a modified ar- 45 rangement of the retainer and members upon the chair to coact therewith; Fig. 7 is a section substantially on the line 7, 7, in Fig. 6, and Fig. 8 is a rear view of Fig. 7.

The numeral 1 indicates a chair seat 50 shown provided with a back 2 and having one or more legs 3 at the outer or rear portion adapted to rest at 4 outside of the window. The seat 1 is provided with one or more members 5, shown in Figs. 1 to 4 bent 55 in substantially Z-form, having their free ends 5^a spaced below seat 1 and projecting

forwardly in position to enter the corresponding openings 6^a in retainer or bar 6 that is secured lengthwise upon the window sill member 4^a, as by screws. I have shown 60 seat 1 provided with two members 5, and retainer or bar 6 having two openings 6^a spaced to correspond with the members 5. Adjacent to the forward edge of seat 1 is a clamping device shown comprising a bracket 65 or the like 8 secured upon the bottom of the seat, as by screws or bolts, and having a threaded opening receiving a screw 9 extending longitudinally of the seat, partly beneath the same, and projecting forwardly 70 beyond the seat, said screw having a suitable handle 9^a, and said bracket is provided with a guideway 8^a receiving a clamping slide 10 having its rear portion 10^a extended down in front of the inner end of screw 9, 75 and having its outer or front portion 10^b suitably extended down and shaped to fit against the projecting portion 11 of the window sill 12, the portion 10^b having an opening freely receiving the screw 9. Where the 80 window sill is not provided with such a projecting portion 11 built with the sill, a suitable projection may be fastened on the front of the sill or window frame, as indicated at 13 in Fig. 5, to receive the hooked or bent end 85 portion 10^b of slide 10. At 14 is a spiral spring shown coiled around screw 9 and extending between bracket 8 and the downward portion 10^b of slide 10.

Instead of providing a single retaining 90 bar 6 with a pair of spaced openings 6^a, I may provide two separate retainers each having an opening 6^a and suitably spaced apart, as shown in Fig. 8, and shown secured to the outer edge of the sill member 4^a. In 95 this construction also, instead of the free ends of the projecting portions 5^a of the members 5 extending forwardly beneath the seat, as in Figs. 1 to 4, they extend downwardly, to enter the openings 6^a, which are shown extending upwardly in Figs. 6 to 8 instead of horizontally as in Figs. 1 to 4. For this purpose the end portions 5^a of members 5 are shown extending from the sides of the chair downwardly, and shaped to extend 100 forwardly at an angle to the vertical, the openings 6^a being correspondingly shaped (Fig. 7), whereby when the clamping slide 10 is fitted against the sill and drawn tight, the parts 5^a will be locked firmly in the corresponding openings of the retainer member 6. The retainers 6 may be spaced apart a 105 110

distance greater than the width of the chair seat, the projections 5^a extended correspondingly beyond the sides of said seat, whereby the openings 6^a may be readily seen when the projections 5^a are applied thereto.

My improvements may be made in suitable sizes and adapted to be applied in connection with windows of stone, brick, frame and other buildings, and so proportioned as 10 to readily fit windows of different dimensions, as required, so that the parts may be fitted to a window with little difficulty and without interfering with the ordinary use of the window. While I have shown two 15 members 5 on the chair, and two corresponding retaining openings 6^a to receive the same, it will be understood that any desired number of such members and openings may be provided.

20 When the chair or seat is to be used the screw 9 is unscrewed to permit the hooked end 10^b of slide 10 to extend outwardly as far as required, the projecting ends 5^a of members 5 are then passed through the corresponding opening 6^a of retainer 6, from the outside inwardly, in Figs. 1 to 4, and from the top downwardly in Figs. 6 to 8, then the end 10^b of slide 10 is placed in front of the projecting portion 11 or 13 of or on 25 the window sill, and screw 9 is rotated, pushing against the depending part 10^a of slide 10, thereby causing said slide to move inwardly and its hook-like part 10^b to engage the projecting portion on the front of the 30 sill, whereby the chair or seat is firmly clamped upon the sill in position to enable a person to sit with safety on the chair, with the back 2 of the chair outwardly with respect to the window. When the chair is to 35 be removed the screw 9 is unscrewed, and spring 14 pushes slide 10 outwardly, releasing the hooked part 10^b from the sill, enabling the projections 5^a of members 5 to be released from the retainer, and the chair 40 lifted out from the window.

By means of my improvements a person may fasten the chair in the window and sit upon the chair in the window with safety for cleaning the windows, for receiving the 50 benefits of the fresh air, etc., and my improvements will be found efficient in use, simple in operation, and cheap to manufacture.

Having now described my invention what 55 I claim is:—

1. The combination of a base having means to connect it to a support to prevent the base from rising, a clamping device comprising a bracket secured upon the under part of the base and having a guideway and a threaded opening, a screw fitted in said opening, and a slide in said guideway over the screw, said slide having a rear portion extended downwardly to engage the 60 screw on one side of the bracket and having

a forward clamping portion on the opposite side of the bracket.

2. The combination of a base having means to connect it to a support, a clamping device comprising a bracket secured upon the under side of the base and having a guideway and threaded opening thereunder, a screw fitted in said opening and projecting on opposite sides thereof, a slide in said guideway above the screw, said slide having a rear portion extended downwardly to engage the inner end of the screw behind the bracket and having a forward clamping portion receiving the outer portion of the screw, and a spring interposed between said bracket and slide.

3. The combination of a base having a forwardly facing hook to connect the base to a support to prevent the base from rising, a clamping device comprising a bracket secured on the underside of the base and having a guideway and a threaded opening thereunder, and a slide below the base fitted in said guideway and having a downward portion at its inner end on one side of the bracket, and a downward hook-like portion at its outer end on the opposite side of the bracket, the latter portion being provided with an opening, a screw passing freely through said opening and meshing in said threaded opening in the bracket, the inner end of said screw being adapted to bear against the inner downward portion of the slide to pull said base and its hook to clamp the base on said support.

4. The combination of a base having a forwardly facing hook to connect it to a support to prevent the base from rising, a clamping device comprising a bracket secured on the under side of the base and having a guideway and a threaded opening thereunder, a slide below the base fitted in said guideway and having a downward portion at its inner end on one side of the bracket, and a downward hook-like portion at its outer end on the opposite side of the bracket, the latter portion being provided with an opening, a screw passing freely through said opening and meshing in said threaded opening in the bracket, the inner end of said screw being adapted to bear against the inner downward portion of the slide to pull said base and its hook to clamp the base on said support, and a spring coiled upon said screw and interposed between 105 and bearing against said bracket and the outer downward portion of the slide to normally press the latter outwardly.

5. In a clamping device the combination of a bracket having a guideway and a threaded opening, with a slide fitted in said guideway and having projecting portions on opposite sides of said bracket, one of said projecting portions having an opening, a screw passing through said opening 110

and meshing in said threaded opening in the bracket, the inner end of said screw being adapted to bear against the projecting portion of the slide opposed to the projecting portion having said opening.

6. In a clamping device the combination of a bracket having a guideway and a threaded opening, with a slide fitted in said guideway and having projecting portions on opposite sides of said bracket, one of said projecting portions having an opening, a screw passing through said opening and meshing in said threaded opening in the bracket, the inner end of said screw being

adapted to bear against the projecting portion of the slide opposed to the projecting portion having said opening, and a spring coiled upon said screw and interposed between the last named projecting portion of the slide and said bracket to normally press the slide in one direction.

Signed at New York city, in the county of New York, and State of New York, this 23rd day of May, A. D. 1913.
